UNITED STATES PATENT OFFICE

158,178

BAKING UNIT FOR FRANKFURTER
SANDWICHESFrederik Christie, Bronx, N. Y., assignor, by mesne assignments, to Irving Levine, New York, N. Y.

Application November 26, 1947, Serial No. 142,807

Term of patent 3½ years

(Cl. D81—10)

To all whom it may concern:

Be it known that I, Frederik Christie, a citizen of the United States of America, and resident of the Bronx, county of Bronx, and State of New York, have invented a new, original, and ornamental Design for a Baking Unit for Frankfurter Sandwiches, of which the following is a specification, reference being had to the accompanying drawing, forming a part thereof, in which

Fig. 1 is a perspective view of a baking unit for frankfurter sandwiches, in closed position, showing my new design;

Fig. 2 is a perspective view of same, with parts thereof in open position.

The back and end of the unit, not visible in the drawing, are substantially plain.

I claim:

The ornamental design for a baking unit for frankfurter sandwiches, substantially as shown and described.

FREDERIK CHRISTIE.
